DIFFERENTIATING DISCHARGE TUBE

Madison Cawein, Fort Wayne, Ind., assignor, by
mesne assignments, to Farnsworth Research
Corporation, a corporation of Indiana

Application July 31, 1944, Serial No. 547,407

7 Claims. (Cl. 250—27)

1

This invention relates to means for obtaining the derivative of an electric signal, and particularly to a novel differentiating electron discharge tube.

It is frequently desired to utilize differentiating means whereby an output signal is obtained which is representative of changes of an electric input signal. Devices of this type are used, for instance, for selecting or separating various types of synchronizing pulses which are required in the transmission of television pictures. Such differentiating means are sometimes used in connection with an integrating means either for selecting different types of electric pulses or for amplifying them.

To this end differentiating networks have generally been used heretofore. In one type of differentiating network a series condenser is employed in connection with a shunt resistor. Differentiation of an electric signal may also be obtained by inductive means such as by transformer coils. However, these prior differentiating networks have the drawback that their frequency response is fairly limited, that is they will only respond to electric signals within a limited frequency range. Another drawback of prior differentiating means is that they can not amplify the input signal simultaneously with the differentiation thereof.

It is an object of the present invention, therefore, to provide a novel differentiating means which has a much wider frequency range than prior devices.

A further object of this invention is to provide a novel electron discharge tube for obtaining the derivative of an electric input signal.

In accordance with the present invention, there is provided an electron discharge tube for differentiating an input signal comprising an evacuated envelope having a collecting anode disposed therein, and an electron gun for developing an electron beam and directing it towards the collecting anode. The intensity of the electron beam is controlled in accordance with the input signal. An electrode is arranged to be responsive to changes in intensity of the electron beam. For deriving an output signal representative of changes of the input signal, an output circuit is operatively connected to the electrode.

For a better understanding of the invention, together with other and further objects thereof, reference is made to the following description, taken in connection with the accompanying drawing, and its scope will be pointed out in the appended claims.

2

In the accompanying drawing, Fig. 1 is a schematic representation of the electron discharge tube of the invention, while Fig. 2 is a set of curves illustrating input and output signal currents and referred to in explaining the operation of the invention.

Referring now more particularly to Fig. 1, there is provided an electron discharge tube 1 comprising an evacuated envelope 2 having a reentrant stem 3. Electron gun 4 has its leads connected through reentrant stem 3 and includes cathode 5, control element or control grid 6 and first anode 7. Cathode 5 is connected to the negative pole of battery 8 through biasing resistor 10. The negative pole of battery 8 is grounded as shown in the drawing. Condenser 11 bypasses resistor 10 to ground. First anode 7 is connected to the positive pole of battery 8, and hence is positive with respect to cathode 5. Second anode or collecting anode 12 is disposed in envelope 2 opposite first anode 7. Collecting anode 12 is connected to battery 8 as shown and may be kept at a slightly negative potential with respect to first anode 7. However, if desired anode 12 may also be kept at the same or even a higher positive potential than anode 7.

Control grid 6 is connected through condenser 13 with the input signal obtained from lead 14. The input signal is impressed across grounded resistor 15 for developing voltage variations which are then used for controlling control grid 6.

Electrode 16 is disposed parallel to the direction of movement of the electron beam developed by electron gun 4 and preferably consists of a metallic coating on the inner wall of envelope 2. Electrode 16 may be electrically connected to first anode 7, as shown and hence has the same potential as anode 7. Although electrode 16 may be omitted if desired it is helpful in the operation of electron discharge tube 1 by keeping the inner wall of envelope 2 at a uniform reference potential which may be that of anode 7 or anode 12. A second electrode 17 arranged in envelope 2 is spaced and electrically insulated from electrode 16. Preferably electrode 17 is ring-shaped as shown.

Electrode 17 is connected to an output circuit including amplifier 20. The output signal obtained from electrode 17 is impressed across grounded resistor 21 and utilized for controlling grid 22 of amplifier 20. Grid 22 is connected through resistor 21 to the negative pole of battery 23, grounded as shown. Cathode 25 of amplifier 20 is connected to ground. The positive pole of battery 23 is connected to anode 26 through re-

sistor 27. The amplified output signal is impressed across resistor 27 and is obtained from lead 28. Magnetic coil 30 surrounds envelope 2. Coil 30 is connected to battery 31 for generating a transverse magnetic field.

The electron discharge tube of the invention operates in the following manner:

By means of electron gun 4 an electron beam is developed in the customary manner and is directed towards second anode 12 which collects the electrons and returns them to the electric circuit. Preferably, the potential between anodes 7 and 12 should be zero or even negative so that the electrons do not acquire a high velocity which would require a collecting anode of great heat dissipating capacity. The thus developed electron beam may be focused by magnetic coil 30. However, it may not be necessary to employ a special focusing coil provided the electrons of the beam do not impinge upon either electrode 16 or electrode 17.

The input signal of which the derivative is to be obtained is connected to control grid 6 through condenser 13. The signal is impressed across grounded resistor 15, and the thus obtained voltage variations serve for controlling the intensity of the electron beam developed by electron gun 4. Hence, the intensity of the electron beam is at any moment directly proportional to the instantaneous input signal amplitude impressed across resistor 15.

Fig. 2 shows a set of curves which may be helpful for explaining the manner of operation of the electron discharge tube of the invention. In Fig. 2 the current has been plotted against time as indicated, and the lower curve represents the input signal or the electron beam current, while the upper curve of Fig. 2 represents the output signal current. As long as the electron beam current remains constant no charge is induced in electrode 17. However, when the beam intensity changes from the horizontal curve portion 33 to transient curve portion 34 a corresponding positive charge is induced in electrode 17. A change of the electron beam current corresponds to a change of the electron density of the beam. Accordingly, when a region of higher electron beam density approaches electrode 17, the induced positive charge increases until the region of higher beam density passes through electrode 17 whereupon the induced positive charge decreases again, as shown in the upper curve 35 of Fig. 2. Hence, curve 35 is the derivative of curve portion 34. Again, when the beam intensity remains constant, as shown in curve portion 36, no charge is induced in electrode 17. When the intensity of the electron beam current is reduced again, as shown in transient curve portion 37, a corresponding charge of opposite sign is induced in electrode 17, as represented by curve 38 of Fig. 2. In this manner current impulses are produced in the output circuit of electrode 17. We may assume that electrode 17 is capacitively coupled to the electron beam in such a manner that electrons of the beam will not impinge upon it.

The current impulses produced in the manner explained above are impressed across grounded resistor 24, and the resulting voltage variations are amplified in amplifier 20 in the customary manner. The output signal obtained through lead 28 is thus representative of changes in intensity of the electron beam which in turn corresponds to changes of the input signal.

Care should be taken that electrodes 16 and 75

17 are arranged so that no electrons from the electron beam will reach them. As indicated in the drawing electrode 17 should have a fairly small width.

5 In view of the fact that variations of the input signal are utilized for controlling the intensity of an electron beam, it will be perfectly obvious that the electron discharge tube of the invention has practically no frequency limitations. The derivative of any input signal may be obtained where the frequency of the input signal lies within the radio frequency range including the high frequencies.

13 The input signal only serves for controlling control grid 6 which in turn determines the intensity of the electron beam. Hence, it may be said that the electron discharge tube of the invention also amplifies the output signal. For further amplifying the output signal a conventional amplifier 20 has been shown, but it is to be understood that the discharge tube of the invention may be used without such a supplemental amplifier arrangement.

23 While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An electron discharge tube for differentiating a transient input signal comprising an evacuated envelope, a collecting anode disposed in said envelope, an electron gun for developing an electron beam and directing it towards said collecting anode, means operatively connected to said electron gun for controlling the intensity of said electron beam in accordance with said input signal, an electrode of comparatively small width arranged to have a charge induced therein in response to changes in intensity of said electron beam, and an output circuit operatively connected to said electrode for deriving an output signal representative of changes of said input signal.

2. An electron discharge tube for differentiating an aperiodic input signal comprising an evacuated envelope, a collecting anode disposed in said envelope, an electron gun including a control element for developing an electron beam and directing it towards said collecting anode, means operatively connected to said control element for controlling the intensity of said electron beam in accordance with said input signal, an electrode disposed adjacent the path of said electron beam and capacitively coupled to said electron beam to have a charge induced therein in response to changes in intensity of said electron beam, said electrode having a width such that the transit time of the electrons of said beam therethrough is comparatively short and an output circuit operatively connected to said electrode for deriving an output signal representative of changes of said input signal.

3. An electron discharge tube for differentiating a transient input signal comprising an evacuated envelope, a collecting anode disposed in said envelope, an electron gun including a control element for developing an electron beam and directing it towards said collecting anode, means operatively connected to said control element for controlling the intensity of said electron beam in ac-

cordance with said input signal, an electrode disposed adjacent to said electron beam and arranged so that electrons from said electron beam will not impinge upon it, said electrode being arranged to have a charge induced therein in response to changes in intensity of said electron beam and being nonresonant to said input signal, and an output circuit operatively connected to said electrode, said electrode having a small width so that the electrons of said electron beam will pass therethrough in a comparatively short time, thereby to derive an output signal representative of changes of said input signal.

4. An electron discharge tube for differentiating an input signal comprising an evacuated envelope, a collecting anode disposed in said envelope, an electron gun including a control element for developing an electron beam and directing it towards said collecting anode, a first electrode extending substantially between said electron gun and said collecting anode and disposed in such a manner that electrons from said beam will not impinge upon it, means for keeping said first electrode at a constant reference potential, means operatively connected to said control element for controlling the intensity of said electron beam in accordance with said input signal, a second electrode disposed parallel to the direction of movement of said electron beam in such a manner that electrons from said beam will not impinge upon it and spaced and electrically insulated from said first electrode, said second electrode having a comparatively small width and being arranged to have a charge induced therein in response to changes in intensity of said electron beam, and an output circuit operatively connected to said second electrode for deriving an output signal representative of changes of said input signal.

5. An electron discharge tube for differentiating an input signal comprising an evacuated envelope, a collecting anode disposed in said envelope, an electron gun including a control element for developing an electron beam and directing it towards said collecting anode, means for focusing said electron beam, a first electrode extending substantially between said electron gun and said collecting anode and arranged as an inner coating of said envelope in such a manner that electrons from said beam will not impinge upon it, said first electrode being arranged to create a field free space between said electron gun and said collecting anode, means operatively connected to said control element for controlling the intensity of said electron beam in accordance with said input signal, a second ring-shaped elec-

trode disposed parallel to the direction of movement of said electron beam in said field free space in such a manner that electrons from said beam will not impinge upon it and spaced and electrically insulated from said first electrode, said second electrode having a comparatively small width and being arranged to have a charge induced therein in response to changes in intensity of said electron beam, and an output circuit operatively connected to said second electrode for deriving an output signal representative of changes of said input signal.

6. The method of differentiating a transient input signal in an electron discharge tube including an electrode, said method comprising developing an electron beam and directing it so that it does not strike said electrode, collecting the electrons of said beam, controlling the intensity of said beam in accordance with said input signal, limiting the transit time of said electrons through said electrode, inducing a charge in said electrode in response to changes in intensity of said beam, said charge being representative of the derivative of said input signal, and deriving an output signal from said electrode representative of said induced charge.

7. The method of differentiating a transient input signal in an electron discharge tube including an electrode, said method comprising developing and focusing an electron beam so that it does not strike said electrode, collecting the electrons of said beam, controlling the intensity of said beam in accordance with said input signal, limiting the transit time of said electrons through said electrode, inducing a charge in said electrode in response to changes in intensity of said electron beam, said charge being representative of the derivative of said input signal, and deriving an output signal from said electrode representative of said induced charge.
